[57] **CLAIM**

The ornamental design for a portable hose reel frame, as shown and described.

DESCRIPTION

FIG. 1 is a perspective view of a portable hose reel frame showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof.

The broken line representation of a hose reel supported on the hose reel frame and wheels for rendering the portable hose reel is for purposes of illustration only and forms no part of the claimed design.
